UNITED STATES PATENT OFFICE.

ULYSES A. GARRED, OF ANACONDA, MONTANA.

HYDRAULIC CONCENTRATOR.

1,031,113.

Specification of Letters Patent.

Patented July 2, 1912.

Application filed December 22, 1911. Serial No. 667,364.

To all whom it may concern:

Be it known that I, ULYSES A. GARRED, citizen of the United States, residing at Anaconda, in the county of Deerlodge and State of Montana, have invented certain new and useful Improvements in Hydraulic Concentrators, of which the following is a full, clear, and exact description, reference being had to the accompanying drawings, forming a part hereof.

My invention has relation to improvements in slime concentrators; and it consists in the novel features of construction more fully set forth in the specification and 15 pointed out in the claims.

In the drawings, Figure 1 is a side elevation of the apparatus, parts being broken away; Fig. 2 is a top plan, with parts broken away; Fig. 3 is a cross-section on 20 the diagonal line 3—3 of Fig. 1; and Fig. 4 is an enlarged side view, with parts broken, of the lower portion of the supplemental receptacle which treats the concentrates discharged from the primary receptacle.

The present improvement while applicable to the treatment of various materials is particularly directed to the concentration of ore-slimes, the special object in view being to so manipulate the pulp or slime carrying the ore values as to not only eliminate therefrom to the best advantage the light clay particles or colloids which are a great hindrance to the concentration of the ore proper, but to separate the ore values from 30 the sandy components and gangue remaining with the ore after the colloids have been removed.

Stated in general terms the invention contemplates an apparatus in which the slimes are subjected to a preliminary treatment in 40 a vessel or container to which there is imparted a rotary reciprocation about a vertical axis, the slime being introduced thereto in the form of a sheet disposed in a 45 plane at right angles to said axis (that is to say in a horizontal sheet), an ascending column of water flowing through the vessel during the reciprocations of the latter whereby the light colloids are caused to 50 flow over the upper edge of the vessel into a suitable launder, the sandy constituents and ore descending through the rising water column and discharging from the bottom of the vessel into a second container having a 55 similar rotary reciprocation imparted thereto, but preferably about an axis inclined to

the horizontal, the ore concentrates and heavy values discharging through a hollow plug or spigot at the bottom of said vessel and the lighter gangue and sand flowing 60 through the open end of the vessel into a suitable launder. The apparatus however, has identified therewith certain structural details the advantages of which will be better apparent from a detailed description of 65 the invention which is as follows:—

Referring to the drawings, C represents a suitable (preferably) cylindrical receptacle or container terminating in a bottom conical discharge hopper C'. The receptacle wall is 70 provided with an outer ring or flange 1 resting on ball-bearings 2 which traverse an annular race-way in a stationary ring 3 secured to the I-beams 4 and loosely encompassing the receptacle. The mounting of 75 the receptacle in the manner indicated (or any manner equivalent thereto) renders the same easily susceptible to rotary reciprocation about its vertical axis, this reciprocation being effected through a connecting rod 80 or link 5 leading from the eccentric 6 on a vertical drive-shaft S, the latter being provided with a pulley P for the accommodation of a belt B, leading to any suitable motor or engine (not shown). No attempt is 85 here made to illustrate the shaft bearings or means of support for the shaft, as such details fall within the purview of the skilled mechanic.

Secured centrally within the receptacle C 90 by means of straps or braces 7 (or otherwise) is a feed-funnel 8 from the lower end of which depends a pipe 9 closed at the bottom, but being provided above such bottom with a series of peripheral openings o which 95 discharge the liquid pulp admitted into the funnel 8 in the form of a series of radial streams collectively forming a sheet disposed substantially at right angles to the axis of the receptacle, or in other words 100 forming a horizontal sheet of pulp which penetrates the liquid contents of the receptacle. Located at the discharge mouth of the hopper C' is a hollow swivel-joint 10 of any approved design, said joint forming the 105 upper terminal of a stationary chamber 11 to which water under a head or pressure is admitted through the terminal upwardly turned nozzle 12 of a water-feed pipe 13 (provided with a control valve V), the base 110 of the chamber 11 being likewise fitted with a valve V'. The swivel-joint 10 permits of

the rotary reciprocation or panning motion being imparted to the receptacle as is obvious. To prevent the formation of individual or uneven upward currents of water 5 from the nozzle 12 through the receptacle, there is interposed in the path of the said nozzle-discharge a conical spreader or equalizer 14, the apex of the cone being vertically over the nozzle 12 an on the axis of the receptacle, the base of the cone being spaced from the walls of the hopper C by the straps or braces 15 which secure the cone to said hopper. Surrounding the upper end of the receptacle is a launder L which receives 10 the overflow from said receptacle. At different elevations the latter is provided with short valve-controlled discharge pipes or tubes 16, 16, for testing the condition of the contents of the receptacle, said test-tubes 15 discharging into launders L', L', as shown, the intake ends of the tubes being protected by guards or aprons 17 depending into the receptacle, said aprons allowing the concentrates to flow down past the pipe 16, while 20 at the same time permitting the water to flow out of the pipes. In addition to serving as test-tubes, the pipes 16 may be used for purposes of lowering the level of the contents in the receptacle in which event the 25 launders L' would be used to receive the overflow of water mixed with the light colloid or suspended clay tailings.

Operating in conjunction with, and supplementing the action of, the receptacle or 30 tank C is a second or complementary receptacle R mounted on a platform 18 having a supporting surface which allows the receptacle to assume an inclination to the horizontal at an angle substantially as 35 shown, but which may be anywhere between thirty and forty-five degrees, such an angle bringing about the best results in washing the sand from the ore concentrates. The receptacle R rests on roller-bearings 19 mounted 40 in brackets 20, the end-thrust being taken up by the bearing-disk or plate 21 at the upper end of the standard 22 bolted or secured to the floor, the disk 21 being provided with an annular race-way for ball-bearings 22' which are engaged by the collar or ring 23 at the intake of the hopper R' forming the bottom of said receptacle R. The upper open end of the receptacle R is 45 provided with a marginal discharge lip 24 which discharges the overflow into a launder L''. Like the primary receptacle C, the supplemental or complementary one R has imparted thereto a rotary reciprocation about its axis, such reciprocation being affected through the link connection 25, arm 50 26 (coupled to the hopper R'), and the eccentric 27 operated by the shaft S. The two receptacles C and R are thus simultaneously reciprocated about their respective 55 axes from a common shaft, the receptacle R

receiving the pulp discharges from the receptacle C through a bent pipe 28 leading from the chamber 11 into the hopper R', a swivel joint 10' being interposed at the proper point to allow for rotation of the receptacle R. The concentrates or ore values are discharged from the complementary receptacle R through a spigot or nozzle 29 located at the lower corner of the receptacle, the said concentrates being received by a 75 launder N.

The operation of the concentrator may be described as follows:—For convenience we may assume that the receptacle C is full of water and that the overflow carrying the 80 tailings or colloids is over the upper edge thereof into the launder L. The pulp or liquid slime being fed from the mills into the funnel 8 is discharged into the receptacle through the openings o in the form of radiating streams which collectively form a horizontal sheet, thereby thoroughly diffusing the solid materials throughout the water body in the receptacle. During the feed of the pulp into the receptacle as described, the 85 latter has imparted thereto a horizontal rotary reciprocation or panning motion from the shaft S through the eccentric 6 and link 5, this panning in a measure separating the ore values and sandy constituents such as 90 quartz and gangue, from the light clay particles or colloids. The ingredients thus in a measure separated encounter an upward rising current of water in the receptacle, resulting from the upward feed of the water 95 100 escaping through the nozzle 12 of the pipe 13, gravity causing the ore values and sandy components to fall against such rising current, but being insufficient to bring down the colloids which thus escape with the overflow into the launder L. The level of the receptacle contents might of course, be lowered by opening the valve of the upper test-tube 16 and allow the overflow to discharge into the upper launder L'. The 105 110 granular or sandy particles and ore concentrates as they fall through the rising water pass around the equalizer or spreader 14 and falling past the nozzle 12 enter the chamber 11 whence they pass into the pipe 28. The 115 120 equalizer 14 causes the rising current to flow at a substantially uniform rate of speed throughout the entire cross-section of the receptacle so that each falling particle may be subjected to the same current resistance, this 125 equalization resulting in a more perfect concentration. The mixture of ore and sand flowing through the pipe 28 and constituting the preliminary concentrates must of course undergo a second treatment in order 130 that the sand and gangue may be separated from the ore values. This preliminary product is therefore discharged into the complementary receptacle R as already outlined, a rotary reciprocation being likewise im- 130

parted to this receptacle from the shaft S through the connections 25, 26, 27, as described. The plane of rotation (or rotary reciprocation) however of the receptacle R instead of being parallel to the water level x (or to the horizontal) is in a plane which is inclined thereto, thus subjecting the pulp contents of said receptacle to a wave washing action which results in a thorough elimination of the sand and gangue, the same flowing over the lip 24 into the tailings launder L, the ore values or final concentrates discharging through the spigot 29 into the launder N. Should the concentrates tend to adhere to the sloping walls of the receptacle they may occasionally be flushed by a stream of water introduced through the spigot from a hose (not shown).

Having described my invention, what I claim is:—

1. In combination with a rotary reciprocating receptacle provided with a tailings discharge, and with a bottom axial discharge means for the concentrates, means for feeding the pulp into the mass contained in the receptacle in proximity to the axis thereof in streams radiating from said axis, and means for producing a rising current of concentrates may fall toward their point of discharge.

2. In combination with a rotary reciprocating receptacle provided with a tailings discharge, and with a bottom axial discharge means for the concentrates, means disposed about the rotation axis of the receptacle for feeding the pulp into the mass contained in the receptacle in proximity to the axis thereof in streams radiating from said axis in a plane substantially at right angles thereto, and means for producing a rising current of water through which the concentrates may fall toward their point of discharge.

3. In combination with a receptacle having a rotary reciprocation about a vertical axis and provided with an upper tailings discharge and a bottom axial discharge means for the concentrates, a stationary chamber below said bottom discharge means, a hollow swivel joint connecting said chamber with said bottom discharge means, a water-feed pipe discharging through the chamber into the receptacle, a spreader disposed above the point of discharge from the water-feed pipe, a pulp-feed pipe disposed about the axis of and extending into, the receptacle and closed at the bottom, the walls of the pipe above said closed bottom being provided with openings for the radial discharge of the pulp into the receptacle, the concentrates discharging from the chamber aforesaid below the point of influx thereinto of the water from the water-feed pipe.

4. In combination with a receptacle hav-

ing a rotary reciprocation about a vertical axis and provided with a tailings overflow, and with a bottom axial discharge means for the concentrates, means disposed about the rotation axis of the receptacle for feeding the pulp into the mass contained in the receptacle in proximity to the axis thereof in substantially a horizontal sheet having its center at the vertical axis aforesaid, and means for introducing a current of water into the receptacle from a point in the path of the concentrates discharge, whereby the concentrates fall through such current under the action of gravity.

5. In combination with a receptacle having a rotary reciprocation about a vertical axis and provided with a tailings overflow, and with a bottom axial discharge means for the concentrates, means disposed in proximity to the rotation axis for feeding the pulp into the mass contained in the receptacle in proximity to the axis thereof in substantially a horizontal sheet having its center at said vertical axis, means for introducing a rising current of water into the receptacle from a point in the path of the concentrates discharge, and means for equalizing the intensity of said rising current throughout the cross-section of the receptacle.

6. In combination with a receptacle having a rotary reciprocation about a vertical axis and provided with an upper tailings discharge and a bottom axial discharge means for the concentrates, a stationary chamber below said bottom discharge means, a hollow swivel joint connecting said chamber with said bottom discharge means, a water-feed pipe discharging through the chamber into the receptacle, a pulp-feed pipe disposed about the axis of and extending into, the receptacle and closed at the bottom, the walls of the pipe above said closed bottom being provided with openings for the radial discharge of the pulp into the receptacle, the concentrates discharging from the chamber aforesaid below the point of influx thereinto of the water from the water-feed pipe.

7. In combination with a cylindrical receptacle having a rotary reciprocation about a vertical axis and terminating in a bottom conical hopper, a stationary chamber below said hopper, a hollow swivel joint connecting the hopper to the chamber, a water-feed pipe discharging a current of water through the chamber into the receptacle, a conical spreader or equalizer disposed above the point of water discharge and secured to and spaced from the walls of the hopper, a pulp-feed pipe disposed about the axis of and extending into, the receptacle and closed at the bottom, the walls of the pipe above said closed bottom being provided with openings for the dis-

charge of the pulp in radial lines at right angles to the axis of the receptacle or in a horizontal plane, the concentrates discharging from the chamber aforesaid below the point of influx thereto of the water from the water-feed pipe, the receptacle being provided with an overflow for the tailings.

In testimony whereof I affix my signature, in presence of two witnesses.

Correction in Letters Patent No. 1,031,113

It is hereby certified that in Letters Patent No. 1,031,113, granted July 2, 1912, upon the application of Ulysses A. Garred, of Anaconda, Montana, for an improvement in "Hydraulic Concentrators," an error appears in the printed specification requiring correction as follows: Page 3, line 29, before the word "concentrates" insert the words *water through which the*; and that the said Letters Patent should be read with this correction therein that the same may conform to the record of the case in the Patent Office.

Signed and sealed this 23rd day of July, A. D., 1912.
